UNITED STATES PATENT OFFICE.

JOHN C. WHITRIDGE AND GEORGE T. JOHNSON, OF COLUMBUS, OHIO, ASSIGNEES TO
THE BUCKEYE STEEL CASTINGS COMPANY, OF COLUMBUS, OHIO, A CORPORATION.

CAR-TRUCK.

1,079,199.

Specification of Letters Patent. Patented Nov. 18, 1913.

Application filed August 8, 1912. Serial No. 783,882.

To all whom it may concern:

Be it known that we, JOHN C. WHITRIDGE and GEORGE T. JOHNSON, of Columbus, in the county of Franklin and State of Ohio, have invented certain new and useful Improvements in Car-Trucks; and we do hereby declare the following to be a full, clear, and exact description of the invention, such as will enable others skilled in the art to 10 which it appertains to make and use the same.

Our invention relates to improvements in car trucks of the six wheel or three axle type, the object being to provide a construction that will be strong and comparatively cheap to manufacture and assemble, and that will distribute the heavy loads it is specially designed to carry, over a greater stretch of track than is the case with four 20 wheel trucks, thus making it practical to carry unusually heavy loads, much greater than is now the general practice, without requiring extensive improvements in tracks and bridges.

It is well known that to carry a load which is concentrated over a short area or length of track, a stronger and more expensive track or sub-construction, is necessary than if the load were distributed over 30 a greater area or length of track. It is also well known that it is economical to carry as much of certain kinds of freight in one vehicle as possible, and it is our aim to accomplish both results in the simplest and 35 most inexpensive way by evenly distributing the load of the car over a greater length of track.

Our invention therefore consists in a truck side frame composed of three equalizing members, each having an axle box, and each end member being partly supported by and flexibly connected with the central member.

Our invention further consists in the parts and combination of parts as will be more fully explained and pointed out in the claims.

In the accompanying drawings, Figure 1 is a view in side elevation of the truck; 50 Fig. 2 is a view in plan of the same; Fig. 3 is a side view of one end member; Fig. 4 is a top plan of the same; Fig. 5 is a side view of the central member; Fig. 6 is a top plan of the same, and Figs. 7 and 8 are

views in side elevation and plan respectively of a modified form.

1 and 2 are the end members, each of which is formed with, or constructed to carry a journal box 1^a, for the end axles of the truck. These journal boxes may be 60 cast integral with the members 1 and 2 of the side frame, or the latter may be provided with any of the well known constructions adapted to receive axle boxes.

Each end member 1 and 2, is provided 65 with a spring support and housing 4 and with an arm 5, the latter being provided at its free end with a bearing 5^a. These arms or extensions 5 of the members 1 and 2, are as shown in Fig. 4, not in line with the 70 shorter arms which carry the journal boxes 1^a, but are preferably offset so as to permit them to extend parallel and alongside of each other as shown in Fig. 2. The shorter arms of the two members 1 75 and 2 are in the same plane, while in the construction illustrated, the longer arms are located at opposite sides of a vertical plane passing centrally through the shorter arms of the members as clearly shown in 80 Fig. 2. The arms 5 of the members 1 and 2 need not necessarily be offset as shown, as the extended arm of one may be bifurcated to permit the extended arm of the other to pass through the bifurcation and engage 85 the far end of the central equalizing member 3, as shown in Figs. 7 and 8, and such other changes as may be necessary or advisable to accommodate this construction.

The central member 3 is provided centrally with a journal box 3^a, and at its ends, at opposite sides of the journal box, with the bearings 3^b on which the end bearings 5^a of the end members 1 and 2 rest. This central member 3 is also provided at each 95 end with the upwardly projecting parallel ears 3^c, between which the bearing ends 5^a of the end members 1 and 2 rest, and these ears 3^c are each provided with a hole for the passage of a pin or bolt which passes 100 through said holes, and through the elongated holes 5^b in the end bearings 5^a of the members 1 and 2. This particular construction with parallel ears is not essential, as the parallel ears may be on the end members instead of on the central member, or any other suitable or equivalent construction may be used. The two arms of the

central member 3, are located out of line as shown in Fig. 6, so that one arm will rest in the vertical plane of the longer arm of member 1, and the other in the vertical plane of the longer arm of the other member 2. If however the longer arm of one end member 1 or 2, of the side frame should be bifurcated to receive the longer arm of the other end member as shown in Figs. 7 and 8, the two arms of the central member would under such condition be in alinement with each other.

The central member 3 is located between and in line with the two end members 1 and 2 with the longer arms 5 of each end member passing over the central member 3 and secured thereto by a pin or bolt, which lock the three members together and prevent them from becoming relatively disarranged in the event of a derailment. By this arrangement the several members of each side frame are flexibly connected so that each is free to rock, and will rock or swing to accommodate the truck to inequalities in the track. Each end member extends across the center member and bears on the latter adjacent its ends, so that part of the load on each end member 1 and 2 is transferred to the central member 3.

Each member of the side frame has a journal box for an axle, and each end member is provided with a spring housing in which the springs 6 are located. These springs carry the cross members or bolsters 7, which latter pass from one side frame to the other in the well known manner, and the two bolsters thus supported carry the center plate 8, which is secured at its ends centrally to the two bolsters. The two bolsters 7 are also connected outside of the side frames by the side bearing members 10, each of which is flanged at its free ends. The bolster ends are entered between these flanges, and as the bolsters are rigidly secured to the flanges, the latter form outer guides for the bolsters which bear against the columns of the side frames and assist in holding the frames in their assembled position. The primary object however of the side bearing members 10, is to prevent the car body from rocking, when in place on the trucks.

It is important in truck construction of the type herein shown, to distribute the load as nearly as possible, equally upon the several journals, and to do this it is necessary that the distance from the center line of the springs 6 carrying the bolsters 7, to the bearing ends 5 of each end member 1 and 2, be twice as long as the distance from the center line of the springs 6, to the center of axle box 1. With such construction it will be seen, that, with the end arms 5 of the end members 1 and 2 so proportioned the longer arms which bear on the central member 3,

will each impart to the axle of the latter half as much of the load as will be borne by each end axle. In other words, each end axle will bear two-thirds of the load falling on the side frame member to which it is connected, and each end member will transmit one-third of the load on it to the axle of the center member.

The end members 1 and 2 are free to turn or rock on the end journals, and the central member 3 is free to rock on the central journals, and the connection between the end members and center member is such, that, each follows the movements of the other so that the members of each side frame of the truck are free to move in a vertical plane within reasonable limits without throwing any undue stresses on each other, and without disturbing the proper relation of the parts or impairing the utility of the structure.

It is evident that changes in the construction and relative arrangements of the several parts might be made without avoiding our invention and hence we would have it understood that we do not restrict ourselves to the particular construction and arrangement of parts shown and described, but,

Having fully described our invention what we claim as new and desire to secure by Letters-Patent, is:—

1. A side frame for car trucks consisting of two end members and a center member, each end member having an arm extending over the center member and bearing on the latter at the far side thereof.

2. A side frame for car trucks consisting of two end members and a center member, each end member having an arm extending over the center member and flexibly connected to the same at the far side thereof.

3. A side frame for car trucks composed of three flexibly connected equalizing members, each end member bearing on the central member at the far side of the latter.

4. A side frame for car trucks composed of three connected equalizing members, each end member being flexibly connected to the central member at the far side of the latter.

5. A side frame for car trucks composed of three equalizing members, each end member having an arm extending over the center member and flexibly connected to the same at the far side thereof.

6. A car truck the side frames of which are each composed of three equalizing members, each member having a journal box and the two end members flexibly connected to the central member at the far side thereof.

7. A car truck the side frames of which are each composed of three equalizing members, each having a journal box, the central member having a bearing at each end, and the two end members each having an arm

adapted to extend over the central member and bear on the end bearing at the far side thereof.

8. In a car truck of the three axle type, the side frames of which are composed of end and central equalizing members, each supported on an axle, the end members being supported at the outer ends on their axles, the inner ends of said end members projecting over the center member to the far ends of same, and secured to the latter.

9. A side frame for car trucks composed of three equalizing members, each having an integral axle box, the inner ends of each end member passing over the central member and flexibly connected to the far end of same.

10. In a car truck of the three axle type, the combination of the side frames, each composed of two end members and a central member each end member bearing on the central member at the far side of the latter

and cross members and mounted on springs in the end members of the side frames.

11. In a car truck of the three axle type, the combination of the side frames, each composed of two end members and a central member each end member having a flexible connection with the central member at the far side of the latter, an axle box in each member, springs in housings in the end members, cross members resting on said springs, and side bearing members connecting the ends of the cross members.

In testimony whereof, we have signed this specification in the presence of two subscribing witnesses.

JOHN C. WHITRIDGE.
GEORGE T. JOHNSON.
